UNITED STATES PATENT OFFICE.

WILLIAM R. HUTTINGER, OF PHILADELPHIA, PENNSYLVANIA.

HIGH-VOLTAGE SWITCH.

Application filed June 25, 1924. Serial No. 722,281.

My invention relates to switches, and it has particular relation to high-voltage electric switches.

In its broad aspect, one object of my invention is to provide an electric switch which is characterized by its ruggedness of construction, yet relatively light weight; by its particular applicability to high tension lines having exceedingly high voltages, say 155,000 volts and over; and by its adaptability to remote control systems.

Another object of my invention is to provide a high-tension switch which is provided with improved means for avoiding accumulations of ice, snow or sleet on the engaging surfaces of the contact elements of such switches.

A further object of my invention is to provide an improved construction wherein the usual insulator strains incident to the operation of the switch are absorbed in the metallic portion thereof.

A still further object of my invention is to provide an electric switch which is characterized by the provision of relatively movable contact members, one of which is pivotally mounted and provided with a pivoted contact portion movable into and out of engagement with the other of said contact members.

A still further object of my invention is to provide a switch of the class described comprising a pair of relatively movable contact members, one of which is provided with a pivoted contact portion cooperating with the other of said contact members, and common actuating means for the pivoted contact portion and the contact member carrying the same, the movement of said contact portion being independent of that of the supporting contact member within predetermined limits.

With these and other objects and applications in mind, my invention further consists in the details of construction and operation and arrangement, hereinafter described and claimed and illustrated in the accompanying drawings, wherein,

Figs. 1 and 2 are top plan and side elevational views, respectively, of a high-voltage switch embodying my invention;

Fig. 3 is an enlarged detail longitudinal sectional view of the cooperating contact por-

tions and their supporting parts shown in the previous figures, the sectional plane being taken on the line III—III of Fig. 4; 55

Fig. 4 is a horizontal sectional view taken on the line IV—IV of Fig. 3; and,

Fig. 5 is a view similar to Fig. 3 of a modification.

In the illustrated form of embodiment of 60 my invention shown in Figs. 1 to 4 of the drawing, a horizontally positioned beam 1, which may be supported on the top of a transmission line tower (not shown), provides a 65 rigid support for spaced insulator-stacks 2 and 3. A supporting bracket 4 is mounted on the upper end of the insulator-stack 2 and it is provided with a substantially horizontal upper surface 5.

A stationary contact member 6, which has 70 been shown in this instance as a laminated brush provided with a contact engaging face 7, is rigidly secured to a supporting block 8 by means of a pair of clamping screws 9. The supporting block 8 may be mounted on the 75 bracket surface 5 by means of screw members 11, so that the stationary contact member 6 extends towards the insulator-stack 3. The block 8 may be provided with a rearwardly extending flange 12 which provides a mounting 80 for the usual terminal connection 13.

The contact engaging face 7 of the stationary contact element 6 is adapted to engage a co-acting face 14 of a movable contact portion 15 of a switch blade 16, a main body portion 85 17 of which is mounted to move in a vertical plane on a pivot pin 18 carried by a bracket 19 mounted on the upper end of the insulator-stack 3, as will appear more fully hereinafter.

The main body portion 17 of the switch 90 blade 16 preferably comprises longitudinal extending members 21 and 22, corresponding ends of which are secured in lugs 23 and 24 perforated to receive the pivot pin 18, whereby the switch blade 16 may be pivotally 95 mounted. The bracket 19 is provided with spaced lugs 25 and 26, which are perforated to receive and support the pivot pin 18, and which are positioned intermediate the lugs 23 and 24. The latter may be further secured 100 in position by means of clamping nuts 27 and 28. A terminal connection 29 for the switch blade 16 may be mounted on the supporting bracket 19 and it is connected by

means of conductors 31 to the lugs 23 and 24.

The opposite ends of the members 21 and 22 are rigidly secured in tubular portions 32 and 33, respectively, of a connecting member

34. Referring to Figs. 3 and 4, which illustrate in detail certain important features of my invention, it may be seen that the connecting member 34 terminates in a housing or casing 35. The latter is provided with a pivot pin 36 which is mounted in bearings 37 and 38 formed in the upper portion of the side walls of the housing 35. The pivot pin 36 has rigidly secured thereto the movable contact portion 15 of the switch blade 16, which comprises a substantially horizontal section 39 carrying the contact engaging face 14 and the substantially vertical section 41 which is keyed to the pivot pin 36. The electrical connection between the movable contact portion 15 and the main body portion 17 may be made more perfect by means of a flexible cable 42 which extends from the vertical section 41 to an adjacent wall of the housing 35.

25 The lower portion of the housing 35 is removed to provide an opening 43 through which the horizontal contact section 39 may pass as it enters and leaves the protecting housing 35. Fig. 3 illustrates in solid-line 30 the movable contact portion 15 in its extended position, wherein the coacting contact surfaces 7 and 14 are in engagement, while Fig. 2 shows in dot-and-dash line the retarded position in which the horizontal portion 35 39 is in the housing 35.

The switch blade 16 may be supported in the solid-line position, wherein the pivoted contact portion 15 is in engagement with the stationary contact member 6, by means of flanges 44—44, which extend outwardly from the lower side portions of the housing 35. The flanges 44—44 engage the upper end portions 45 of screw members 46—46 which are mounted in threaded perforations 48 formed in spaced shoulder portions 49—49 of the bracket 4. The spacing of the shoulder portions 49—49 is sufficient to permit the horizontal contact section 39 of the pivoted contact portion 15 moving therebetween as it is actuated to and from the protective housing 35. The adjustable screw supports 46—46 may be secured in a desired vertical position by means of lock-nuts 51.

55 The stationary contact element 6 may be protected from ice and snow by means of a housing 52'. The housing 52' may comprise, for example, a hood 52 and the bracket 4. The hood 52 is provided with lugs 53—53 extending from the opposite sides thereof and 60 perforated to receive clamping screw members 54, the latter being secured in the spaced horizontal shoulder portions 49—49 of the main bracket 4. A side portion 55 of the hood 52 adjacent to the housing 35 is provided with an opening 56 so as to permit the

insertion and removal of the horizontal section 39 of the pivoted contact portion 15 to and from the protecting hood 52.

The above noted movable switch parts may be actuated by a third insulator-stack 57 which may be mounted intermediate the insulator-stacks 2 and 3 for rotation about a vertical axis substantially parallel to the plane of movement of said movable switch parts. A lower end of the insulator-stack 57 70 may be mounted on an anti-friction thrust bearing 58 carried by the supporting structure 1, and it is provided with a toothed end portion 59 adapted to mesh with a beveled gear wheel 61 mounted on a shaft 62 driven by a motor (not shown). The upper end of the insulator-stack 57 may be provided with a vertically extending shaft portion 63 which is journaled in an antifriction bearing 64 carried by arms 65 and 66 forming integral 80 extensions of the bracket 19.

It is desirable that the actuating insulator-stack 57 and the movable switch parts 15 and 16 be so operatively associated that the torsional strain in the insulator-stack 57 at no 90 time reach a dangerous value with the ordinary accumulations of ice or snow present. To this end, the insulator-stack 57 is operatively associated with the main body portion 17 and the pivoted contact portion 15 of the 95 switch blade 16 by mechanism 67 which is so designed that said switch parts will move only a small amount in response to a relatively large movement of the actuating insulator-stack 57. That is to say, mechanism 100 105 67 is so designed that the mechanical advantage of the actuating insulator-stack 57 is very large. As a matter of illustration, the mechanism 67 may be shown as a special form of screw gearing.

This so-called "screw jack connection" 67 between the insulator-stack 57 and the movable switch parts 15 and 17 involves the use of a worm 68, which is mounted on the upper end of the shaft 63, and a worm wheel 69, 110 which has been shown as a quadrant pivotally mounted on the portion of the pivot pin 18 intermediate the bracket lugs 25 and 26. The quadrant 69 is provided with an upwardly extending arm 71, the end of which is operatively associated by means of a link 72 with the free end of an operating arm 73. The arm 73 is keyed to an extension portion 74 of the pivot pin 36 positioned externally of the housing 35 and it is secured in position by means of a lock nut 75 and washer 76 (Fig. 4), whereby the pivoted contact portion 15 may be actuated in accordance with the rotation of the insulator-stack 57.

The quadrant 69 may be provided with 125 pairs of oppositely extending arms 77 and 78, which are respectively positioned at predetermined distances from the lower and upper sides of the body portion 17 of the switch blade 16, whereby the arm 71, and conse- 130

quently the pivoted contact portion 15, may be moved a predetermined distance prior to the actuation of the switch blade 16 as a whole through the engagement of one or the other 5 of said pair of arms 77 and 78 therewith.

As shown in the drawing the worm 41 has a relatively flat pitch, so that the worm 41 and wheel 39 may be non-reversing under the action of the switch blade 9. This non-reversing or non-overhauling characteristic is 10 particularly important since the switch blade 9 is locked in any desired elevated position regardless of whether or not power is applied to the actuating insulator-stack 30.

15 When the high-tension switch embodying my invention is in the closed position shown in solid-line in Figs. 1 to 4 inclusive, the pivoted contact portion 15 is in engagement with the stationary contact element 6, and the pairs 20 of arms 77 and 78 are spaced equally from opposite sides of the members 21 and 22 of the main body portion 17. If the insulator-stack 57 is now turned, the quadrant 69 and the lever arm 71 are moved, causing the pivoted 25 contact portion 15 to move out of engagement with the stationary contact element 6 and into the protecting housing 35. At this instant, the lower arms 77 engage the underside of the main body portion 17 of the switch 30 blade 16, so that the continued movement of the quadrant 69 causes the main body portion 17 to move in a vertical plane about the pin 18 as a pivot, carrying with it the pivoted contact portion 15. Such movement may 35 be continued until the switch blade 16 has been actuated a desired distance from the stationary contact element 6, one such position being shown in dot-and-dash lines in Fig. 2.

When it is desired to close the high-tension 40 switch embodying my invention, the direction of rotation of the insulator stack 57 is reversed, whereupon the movable switch blade 16 by reason of its weight follows the downwardly moving supporting arms 77. 45 However, should there be a tendency for the switch blade 16 to remain in its raised position, the upper arms 78 engage the top side of the main body portion 17 and forcibly actuate the same downwardly. Experience has 50 shown that once the switch blade 16 has started to move downwardly, the weight thereof is sufficient to cause the same to follow the downwardly moving supporting arms 77.

The lowering of the switch blade 16 is continued until the shoulders 44—44 of the housing 35 engage the adjustable supporting screw members 46—46. The housing 35 is thus supported on the housing 52'. The continued movement of the quadrant 69 causes 60 the supporting arms 77 to be actuated out of engagement with the main body portion 17, and it also causes a forward movement of the lever 71, whereby the section 39 of the pivoted contact portion 15 may be moved out 65 of the protective housing 35 and into engage-

ment with the stationary contact element 6 to complete the closing of the switch. When the switch has been thus closed, the operation of the actuating insulator-stack 57 is automatically discontinued in the usual manner. 70 When the switch is to be again opened, the foregoing procedure is repeated.

The modification shown in Fig. 5 differentiates over that of the preceding figures in the design of the switch contact portions. In the 75 present instance, the laminated stationary contact element 6 of the preceding figures is replaced by a stationary contact element 79 which comprises a bifurcated portion provided with spring contact blades 81—81 of 80 usual design. A further modification is in the mounting of a blade contact 82 on the end of the horizontal section 39 of the pivoted contact portion 15, so that the rocking movement of the latter causes the blade portion 82 85 to be inserted between and removed from the spring blades 81—81. The operation of the structure of this figure is otherwise as that described for the preceding figures.

A further advantage of my invention re- 90 sides in the fact that the usual strains, which are introduced in the insulator-stack 2 upon the closing of the switch, are avoided inasmuch as such strains are substantially absorbed in the supporting bracket 4 and parts 95 immediately associated therewith. This desired result is brought about by providing a switch design as set forth hereinabove, wherein the strains, which are introduced in the bracket 4 by the engagement of the pivoted 100 contact portion 15 and the stationary contact element 6, are canceled by the opposite strains which are introduced in the bracket 4 through the supporting of the outer end of the main body portion 17 of the switch blade 16 on the 105 screw members 46—46, as will be readily understood by those skilled in the art. Reference is herein made to my co-pending application, Serial No. 689,256, filed Jan. 29, 1924, wherein the feature of a worm-and-wheel or 110 screw-jack connection in the switching apparatus is described and claimed broadly.

While I have described certain forms of embodiment of my invention in detail and while I have pointed out certain of the most 115 obvious principles and purposes thereof, I do not intend that the language employed in the following claims shall be limited to the precise features described, but I intend that the claims shall be construed to cover all combinations which are fairly included in the language thereof when read in connection with the prior art regardless of the details and functions mentioned in the description or illustrated in the drawing. 120

I claim:

1. A switch comprising a stationary switch element, a movable switch element provided with a pivoted contact portion adapted to contact with said stationary switch element, and 130

- means for successively actuating said pivotally mounted contact portion out of engagement with said stationary switch element and thereafter moving said movable switch element as a whole.
2. An electric switch comprising a pair of stationary insulators disposed in spaced relation, stationary and movable contact elements respectively carried by said insulators, 10 said movable contact element terminating in a housing and provided with a contact portion movable relative to said housing, said contact portion being adapted to co-act with said stationary contact element, an actuating insulator, and means including self-locking gearing for operatively associating said actuating insulator and said movable contact element and pivoted contact portion.
3. In an electric switch, a movable contact element, a housing supported by said movable contact element and constituting a part thereof, and a contact portion pivotally mounted in said housing and movable from said housing into an effective position.
4. A switch including a movable contact element, a contact portion pivotally mounted thereon and provided with an operating arm, and common actuating means for said operating arm and said movable contact element, permitting relative movement therebetween.
5. In an electric switch, the combination with a stationary contact element, of a supporting bracket therefor provided with spaced supporting points, and a movable contact element comprising a main body portion and a relatively movable contact portion, said contact portion coacting with said stationary contact element, said main body portion being adapted to rest on said supporting points.
6. A stationary contact element, a supporting bracket therefor provided with spaced supporting points adjustably mounted therein, a movable contact member comprising a main body portion and a relatively movable contact portion, said contact portion being adapted to co-act with said stationary contact element, said main body portion being adapted to engage said supporting points.
7. In combination, a stationary contact element, a supporting bracket therefor, and a movable contact member provided with a housing adapted to engage said supporting bracket, said contact member having a relatively movable contact portion supported in said housing and movable into engagement with said stationary contact element.
8. A stationary contact element, a supporting bracket therefor, a pivoted contact member provided with a housing on the free end thereof adapted to rest on said supporting bracket, a contact portion pivotally mounted in said housing and movable therefrom into engagement with said stationary contact element, and means for actuating said mov-
- able contact portion into said housing and thereafter actuating said pivoted contact member out of engagement with said supporting bracket.
9. A pivoted contact member terminating in a housing, a contact portion pivotally mounted therein and provided with an operating arm, a second arm operatively associated with said first-mentioned arm, and means for actuating said arms and said movable contact member according to a predetermined sequence.
10. A pivotally mounted contact member terminating in a housing, a contact portion pivotally mounted therein and provided with an operating arm external to said housing, and means for actuating said arm independently of said movable contact member to move said contact portion into and out of said housing.
11. In an electric switch, the combination with a stationary contact element, a supporting bracket therefor, and means for enclosing said stationary contact element, of a cooperating movable contact member provided with a housing, a relatively movable contact portion positioned in said housing but movable therefrom into engagement with said stationary contact element, said bracket providing spaced supporting points for said housing, and common actuating means for said movable contact member and said contact portion.
12. In combination, relatively movable switch members, of which one is provided with a movable contact portion, housings for one of said switch members and said movable contact portion, respectively, one of said housings constituting a support for the other, and actuating means for at least one of said switch members including worm-and-wheel mechanism.
13. In combination, relatively movable contact members, of which one is provided with a pivoted portion, and actuating means for at least one of said contact members including worm-and-wheel mechanism, said means having a lost-motion connection to said last-mentioned member.
14. A switch comprising relatively movable contact members, of which one is provided with a pivoted portion, and screw-jack means for actuating at least one of said contact members, said means having a lost-motion connection to said last-mentioned member permitting a predetermined relative movement between the latter member and said pivoted contact portion.
15. In combination, relatively movable contact members, of which one is provided with a housing and a pivoted portion movable in said housing, and actuating means for at least one of said contact members including worm-and-wheel mechanism.
16. In combination, relatively movable contact members, of which one is provided

with a housing and a pivoted portion movable in said housing, and actuating means including screw-jack mechanism for relatively and bodily moving said last-mentioned member and pivoted portion.

5 17. In combination, relatively movable contact members, of which one is provided with a pivoted portion, and screw-jack means for actuating at least one of said contact members, said means having a lost-motion connection to said last-mentioned member, the latter member being provided with a housing for said pivoted portion.

10 18. A switch comprising a pair of stationary insulators, contact elements respectively supported on said insulators, one of said contact elements being movable and provided with a pivoted contact portion, an actuating insulator, and means including worm-and-wheel mechanism for operatively associating said actuating insulator and said movable contact element.

15 19. A switch comprising a pair of supporting insulators, contacts respectively carried by said insulators, one of said contacts being movable and provided with a protective housing, an actuating insulator, and means for establishing a screw-jack connection between said actuating insulator and said movable contact element.

20 20. A switch comprising a pair of insula-

tors, contact elements respectively mounted thereon, one of said contact elements being movable and provided with a housing and a contact portion movable in said housing, an 35

actuating insulator and means including worm-and-wheel mechanism for operatively associating said actuating insulator and said movable contact element and contact portion.

21. A switch comprising a pair of insulators, contact elements respectively mounted thereon, at least one of said contact elements being movable and provided with a housing and pivoted contact portion, an actuating insulator rotatable about its axis, and means 40 including the worm-and-wheel mechanism for operatively associating said actuating insulator and said movable contact element and pivoted contact portion, said means also including a lost-motion connection. 50

22. In combination, relatively movable switch members, of which one is provided with a relatively movable contact portion, supporting insulator stacks for said switch members, respectively, a housing for one 55 switch member comprising a hood and a supporting bracket, and a housing for said relatively movable contact portion carried by the other switch member and adapted to engage said bracket.

WILLIAM R. HUTTINGER.
